The ornamental design for a dispenser, as shown and described.

DESCRIPTION

FIG. 1 is a perspective view of a dispenser showing our new design;

FIG. 2 is an inverted perspective view thereof;

FIG. 3 is a front elevation view thereof;

FIG. 4 is a back elevation view thereof;

FIG. 5 is a right side elevation view thereof, the opposite side being identical;

FIG. 6 is an enlarged bottom elevation view thereof;

FIG. 7 is an enlarged top elevation thereof; and,

FIG. 8 is an enlarged view of a portion of the design shown in FIG. 3.

In the drawings, the broken lines depict unclaimed subject matter only and form no part of the claimed design.

The broken line circle shown in FIG. 3 indicates the unclaimed boundary of the design that is shown on an enlarged scale in FIG. 8.
